UNITED STATES PATENT OFFICE

SALISBURY M. DAY, OF ROCHESTER, NEW YORK, ASSIGNOR TO GENERAL RAILWAY SIGNAL COMPANY, OF ROCHESTER, NEW YORK

PROJECTOR FOR LIGHT SIGNALS

Original application filed October 17, 1921, Serial No. 508,194. Divided and this application filed December 29, 1924. Serial No. 758,665.

This invention relates to light signals for railway signaling purposes, and more particularly to light projectors for such signals.

Color light signals in their typical form comprise a number of light projecting units with different colored lenses, as red, green, yellow or the like, and the different signal indications are given by lighting the electric lamps of these units one at a time as desired so as to project a beam of colored light. In such a signal, while the energy consumption should be as low as possible, especially where primary batteries are to be used, the signal should be able to give a positive and arrestive indication at a comparatively long range, such as 3,000 or 4,000 feet, and also through a wide angle of spread so as to be visible even though the observer, on account of a curve in the track or other conditions, should not be directly in line with the signal. Also, a satisfactory day light signal should be capable of giving such an indication under most unfavorable light conditions, that is, with a sky background and with strong sunlight shining directly in the face of the signal or observer. These practical working conditions demand an efficient light projecting system; and while a concentrated filament electric lamp affords a satisfactory light source for this purpose, in order to obtain the desirable range of indication and angle of spread with the least amount of energy consumption, it is desirable to utilize as much of the light from the lamp as possible. It will be evident that the ordinary lens is capable of receiving and projecting only a small part of the total light emitted from the filament of the lamp, that is, only a portion of the total spherical candle power of the lamp. The use of reflectors or curved mirrors, in an attempt to use some of the light emitted backward and sidewise of the lens from the lamp, is objectionable in practice because of the tendency to produce false signal indications, commonly termed "phantom" signals. Such phantom signals are caused by light from an outside source, such as sunlight or a locomotive headlight, which passes into the signal and is reflected or diffused back out, making the signal appear as if it were lighted.

Another important characteristic of a color light signal adapted for practical working conditions in railway signaling is the provision of a reserve source of light. The electric lamps of the signal of course burn out from time to time, and rather than have the burning out of a lamp extinguish all indication and make a "dark" signal, it is desirable to have a reserve or auxiliary light source to maintain an indication, sufficiently strong for the engineer to recognize and yet preferably weaker than the regular indication, so as to point out the failure of the main light source.

As the lamps burn out and are replaced, it is essential for a satisfactory indication that the filament of the new lamp in each instance should be in the proper position with relation to the focal point of the lens or other optical device of the signal. Electric lamps manufactured commercially on a large scale, however, do not have their filaments, or more strictly speaking, the luminous center of their filaments, in any definite fixed relation with respect to the bulb or its base; and when a new commercial lamp is inserted in a signal, it is usually necessary to adjust the lamp slightly in some suitable way so as to bring its filament at the desired point. Such adjustment is awkward and expensive, and requires two experienced workmen, one to make the adjustment, and the other to stand at a distance and determine from the appearance of the signal when the proper adjustment has been made. Incidentally, there is also practical difficulty in communicating in a simple and effective manner between the observer and the man at the signal making the adjustment.

In order to satisfy these practical requirements and requisites for day light color light signals above pointed out, it is proposed in accordance with the present invention to provide an arrangement of lenses, conveniently termed a "doublet combination," together with a lamp having a double or duplex convoluted filament symmetrically located with respect to these lenses, so as to utilize a large proportion of the total light emitted from the filament, these double filaments being

preferably constructed so that one will burn longer than the other; and in order to facilitate the replacement of burnt out lamps, the invention contemplates a scheme of manufacture or construction of signals and lamps, so that any lamp may be inserted in any signal, and regardless of inaccuracies in the location of its filament incident of manufacture on a commercial scale, the filament will in every instance be at the proper point with respect to the lens combination of that particular signal.

In the practical application of light signals to the varying conditions of railway signaling, it is found that various aspects and different applications and the like of support for the signal are required. For example, at one time one may want a signal capable of giving two different indications, commonly termed a "two-position" signal, at another time a three-position signal. In order to get these requirements in the simplest manner, and more particularly obviate necessity of manufacturing and keeping in stock a large number of parts to make up the various combinations required, it is proposed in accordance with the present invention to design the light signal casing and other parts so that they are symmetrical and interchangeable and any of the component parts may be combined together directly and without affecting previous adjustments to make up a large variety of combinations or assemblages.

Other features and advantages of the invention will appear as the description progresses.

In describing the invention in detail, reference will be made to the following drawings, in which:—

Fig. 1 is an enlarged front view of a two-unit light signal, portions thereof being broken away for clearness;

Fig. 2 is a side view of the light signal shown in Fig. 1 illustrated in the same manner;

Fig. 3 is a sectional view taken on the line 3—3 of Fig. 4 as viewed in the direction of the arrows;

Fig. 3^a is a fragmentary sectional view on line 3^a—3^a of Fig. 3, viewed in the direction of the arrow;

Fig. 4 is an enlarged view, illustrating the inside bezel ring and the lamp socket and lamp adjustably mounted thereon;

Fig. 5 is a fragmentary sectional view taken on the line 5—5, Fig. 1, and shows the sighting arrangement; and

Fig. 6 illustrates the glass of the sighting device most clearly shown in Fig. 5.

This application is a division of the prior application of Salisbury M. Day, for colored light signals, filed October 17, 1921, Ser. No. 508,194.

According to the preferred embodiment of the invention, the signal is made up in its va-

rious combinations of identical light projecting units, with casings and various adapters such that these units may be assembled together to provide signals giving any desired number and arrangement of indications. One of these units will be first described in detail, before considering the different ways in which the parts of these units may be interchanged.

Referring more particularly to Figs. 1 and 2, each signal unit comprises in general a box-like casing C, which is preferably made of cast iron so as to have the necessary strength and rigidity. This casing C is formed with a large circular opening in its front wall, and is provided with an open back closed by a movable door 1. This door 1 may be connected to the casing C in any suitable manner, but in the construction shown the door is formed with integral lugs at one side which are hinged on cotter pins or the like supported by pairs of lugs integral with one side wall of the casing C, so that the door may be swung back and expose the entire inside of the casing. The door 1 is also preferably provided with a suitable spring hasp fastener 2 for pressing the door inward with a gasket 3 in a groove around the door seated tightly against the edges of the casing C. A ventilating opening 4 (see Fig. 2) is provided in the door 1, and this opening is protected by a suitable bulging cap or weather shield fastened by screws to the door over the opening 4 and also by a screen suitably secured inside of the door.

The top and bottom walls of the casing C are constructed identically, and have a raised ridge 5 around the edge which is accurately machined in manufacture, a central beveled or cup shaped opening 6, and four holes 7. By reason of this construction, two casings C may be fastened together by bolts 8, as shown in Figs. 1 and 2, with their machined ridges 5 contacting and lining up these casings.

A light projecting unit, comprising a lamp and its socket, the inner and outer lenses of the doublet combination, and a suitable hood, is detachably fastened to the front wall of the casing C. This light projecting unit comprises a tubular tapered casting 9, conveniently called a lens barrel, which is formed with an outer flange fastened by four bolts 10 to the front wall of the casing C, as best shown in Figs. 1 and 2. The outer lens 11 of the doublet combination bears around its edges directly against the bottom of a groove or rabbet formed in the larger end of the lens barrel 9. This outer lens 11 is held in place by a retaining member 12 which is fastened to the lens barrel 9 by four screw bolts 13, a gasket 14 of felt or the like, being preferably interposed between this retaining member 12 and the edges of the lens 11. This retaining member 12 is formed with four notches in its edge, as shown in Fig. 1, to receive the heads of the bolts 10 and prevent them from turning.

these bolts being preferably provided with jam nuts. Extending partway around the upper part of the retaining member 12, and integral therewith, is a forwardly projecting flange 12^a to which is fastened by screw bolts 5 a curved sheet metal hood or shield 15. The inner lens 16 of the doublet combination also seats at its edge in a groove or rabbet in the lens barrel 9, and this inner lens is held in place by a retaining member or ring 17, 10 which is fastened by three screws 18 to the lens barrel 9, a similar gasket being interposed between the lens barrel 9 and this lens. It will be noted that the lenses 11 and 16 bear directly against finished surfaces on 15 the lens barrel 9 and the ring 17 fastened thereto, and since these surfaces are accurately formed in manufacture, and the lenses, being molded, are identical, it will be evident that the lenses always have the proper fixed 20 spacing and relation in each signal unit.

The inner and outer lenses 11 and 16 are of the well-known Fresnel or stepped type, the steps or corrugations being formed on 25 the inner surface of the outer lens 11, and the outer surface of the inner lens 16. The outer lens is clear or colorless, while the inner lens is made of glass having the desired shade of red, green, yellow, or the 30 like, for the appropriate signal indications. The purpose of this combination or arrangement of lenses is to utilize as much of the total light rays or flux emitted by the filament as it is practicable to obtain without 35 the use of reflectors and their objectionable tendency to produce "phantom" indications, and without employing movable color screens or other moving parts. In this arrangement 40 of lenses, which may be conveniently termed a "doublet combination" the incandescent lamp, constituting the source of light is located with its filament as close to the inner lens 16 as permitted by the size of the lamp bulb needed to take care of radiation, and 45 also the practical clearances required to allow insertion and removal of the lamp. It will be evident that the closer the filament is to the lens, the greater portion of the total spherical candle power of the filament will 50 be received by the lens; and in the specific construction shown, it can be seen that the cone of light rays falling upon the inner lens embraces a solid angle corresponding approximately to a plane angle of 158 degrees, so that about 40 per cent of the total 55 light flux given off by the filament falls upon the inner lens.

The inner lens 16 is made with its inner surface concave and with prismatic zones of 60 spherical curvature on its outer surface. These zones are designed in accordance with established optical principles so as to converge the light rays emanating from the filament upon the outer larger lens 11. The 65 inner lens has an apparent focus at a point

behind the lamp, preferably at the apex of the angle embraced by the outer edges of the two lenses. The outer lens 11 has its outer convex surface smooth, and is formed with zones on its inner surface 70 of the proper curvature to project an image of light at the focus of the inner lens into a beam of the desired angular spread. Generally speaking, the outer lens has its focus at the same point as the apparent focus 75 of the inner lens; the inner lens producing an image of the filament at said point behind the lamp, and the outer lens producing an image of this image.

Regarding the angle of spread, this is 80 necessary in a light signal for railway signaling purposes, in order that the signal may be seen by the engineer of a train as it approaches the signal, comes around a curve, or is traveling on an up or down 85 grade toward the signal. Of course, as the spread of the beam is increased, its cross section is increased, and consequently for the same candle power, the intensity of 90 the beam is decreased; and these antagonistic factors are proportioned and selected to conform with practical working conditions, so as to provide a light projecting system visible through the desired angle of 95 spread and at the desired range or distance, with a minimum energy consumption. A further point regarding the spread of the signal is that the curvatures of the zones on the lower portion of the outer lens 11 are preferably modified, so as to direct some light downward from the main beam directly in front of the signal, in order that a reasonably strong signal indication may be visible by the engineer of a locomotive pulling directly up to and standing under the signal, this being 100 particularly important where the signal is mounted on a high pole or on a signal bridge.

The lamp 19 employed in each signal unit is preferably formed with a double or duplex concentrated filament. In the particular construction illustrated, two parallel convoluted filaments 20 are secured to the usual pair of lead-in-wires; and these filaments are intended to have a different length of life, 110 being preferably made of a different length or cross section so far as practicable in ordinary manufacture, so as to have different resistances and burn at different temperatures. These filaments 20 are located close together 115 and are positioned symmetrically about the point at which the light source should be located. Both of the filaments are in the lighting circuit, and since one will almost always burn out before the other, the remaining filament constitutes a reserve light source 120 which is strong enough to give a recognizable indication, but weak enough to show that a new lamp is needed. Thus, the double filament lamp, in addition to providing an effi- 125 130

cient and effective concentrated source of light, meets that important requirement of railway signals of providing a reserve source, this reserve source being always available without dependence on the operation of a cut-in relay or other mechanical device. Also, this reserve source is located very near the exact point where the light source should be located, rather than at a considerable distance out of focus, so to speak, as it necessarily must be when afforded by an extra lamp.

Since accurate location of the light source is important in signals of this character, the manner in which the lamp is mounted or supported in the signal should be such as to hold the lamp firmly and positively in the proper position, even though carelessly put in place, or subjected to considerable jar and vibration, while at the same time the lamp should be readily movable to permit replacement. To satisfy these requirements, it is proposed to employ the usual bayonet type lamp base and socket. The lamp base is accurately formed in manufacture, or an auxiliary base or support is attached thereto after manufacture, or in some other suitable way constructed or adapted so that the filament has a definite relation with respect to the surface of the base and pins determining the position of the lamp when inserted in a socket. The pins in the base of the lamp are also located with respect to the plane of the double filament so that this filament faces the lens. The particular design of apparatus for rebasing or constructing such standardized lamps with a uniform and accurate location of their filaments with respect to their bases, and the specific construction of the rebased lamps, forms no part of the present invention, and is described and claimed in applications filed by R. C. Leake, Sept. 24, 1921, Ser. No. 502,955, and by E. W. Moore, Sept. 30, 1921, Ser. No. 504,456 respectively.

The socket or receptacle to receive the lamp is of the usual type and comprises a socket or shell proper 21, which is formed with bayonet slots, and is fastened to a block 22 of porcelain or similar insulating material. In this block 22 is supported the usual spring pressed plunger or contact pin (not shown), which engages the center contact of the lamp and also seats the pins on the lamp base in the bayonet slots. This porcelain block 22 is also provided with the usual terminal posts for wires, and is fastened by two screw bolts 23 (see Figs. 3 and 4) to an angle bracket 24, these bolts passing through enlarged holes in the bracket so as to permit the block to be adjusted to various positions in the plane of the bracket. The angle bracket 24 is secured by bolts 25 at each end to downwardly projecting extensions on the retaining ring 17, the bolts passing through vertical slots in said extensions, so that the bracket may be raised and lowered, or tilted.

The porcelain block 22 is accurately adjusted with the aid of a suitable fixture during manufacture or assembly, so that the axis of the socket shell 21 and the bottoms of bayonet slots have a definite relation with respect to the bezel ring 17, and consequently with respect to the lenses. Such adjustment takes care of any slight variations in size and shape that may occur in commercial manufacture of the porcelain blocks 22, socket shells 21, angle brackets 24, and associated parts. In other words, the lamp socket of each signal is individually adjusted during manufacture in such a way that any lamp, rebased or adapted to fit that type or style of signal, may be put in any socket, and the filament of that lamp will come at the proper point.

In order that the signal may be visible at the desired distance and through the desired angle of spread, it is obvious that the signal should be pointed accurately in the right direction; and on account of variations in conditions, it is ordinarily necessary to adjust and sight each signal. The usual practice of having a workman at the signal to adjust it, and an observer at a distance to check up the adjustment, is cumbersome and inefficient. Not only are experienced observers required for this purpose, but also great difficulty is encountered in providing a simple and effective way of communicating the necessary information from the observer to the signal. To facilitate such adjustment, a simple and effective sighting device for the signal is provided by this invention. This sighting device in general comprises spaced apertures in the casing which are accurately located during manufacture with respect to the lenses, so that the line of sight afforded by this device conforms with the direction in which the beam of light will be projected from the signal. In the particular construction illustrated (see Figs. 5 and 6), a glass disc 26 is fitted in a small circular opening in the front wall of the signal casing C near one upper corner, this disc being held in place by a suitable bezel ring fastened to the casing. At the rear end of the casing C, back of the disc 26, a small peep hole 27 is bored in a small web integral with the casing. The glass disc 26 is preferably provided with a ring 26^a (see Fig. 6) which is sand blasted thereon, painted or otherwise made opaque or nearly so. While one pair of these sighting apertures is sufficient for any one signal, regardless of the number of units making up that signal, for simplicity and convenience in manufacture, it is preferred to provide each unit with these sighting apertures.

Upon looking through the small peep hole 27, the clear glass of the disc 26 outside of the ring 26^a affords a relatively large field for spotting objects and determining a coarse adjustment, while the small hole inside of

the ring 26^a forms a small field for accurate sighting. If desired, the large field may be proportioned to correspond approximately with the area of the beam of light from the signal, so that an observer can determine roughly, at least, how to point the signal so as to be visible from the desired points along the track. This sighting device greatly facilitates the adjustment of the signals for long or short range, curves, grades, and other service conditions, particularly since the sighting device may be used by the workman at the signal who is making the adjustment; and this sighting device, while effective and sufficiently accurate for all practical purposes, is cheap and simple and may be made with a permanent part of each signal unit, thereby making it unnecessary for workmen to carry around special tools and implements for setting up and adjusting signals. In this way, once the lamp socket has been accurately disposed with respect to the lenses, any rebased or standardized lamp may be inserted in this socket, and the filament of that lamp will come at the proper point with respect to the lenses. This is an important feature of the invention, since lamps when manufactured in quantities by commercial methods, do not have their filaments accurately located with respect to their bases, so that when such commercial lamps are put in signals to replace those burnt out, or otherwise unfit for service, an adjustment for that new lamp is ordinarily necessary to obtain an effective light projection; and as this adjustment is difficult to perform in this field, it is evidently of great practical advantage to be able to replace burnt out lamps when necessary by merely putting in another lamp standardized to fit that signal without adjustment.

Another feature of the signal disclosed resides in the provision of an adjustable support for the signal by means of which it may be mounted upon the top of the usual tubular pole, or on a suitable bracket, and turned or tilted in any desired direction. Referring to Figs. 1 and 2, this support or adapter 30 comprises a tubular portion tapered at the upper end and on the inside so as to receive poles or other round supports varying in diameter, the ends of these poles seating tightly against this tapered surface. A plurality of adjusting screws 31, four being shown, are threaded in the tubular portion of the support 30 and are provided with the usual lock nuts. When these screws 31 are loosened, the whole support 30 may be turned around the pole, and by adjusting these screws, the support may be tilted at any desired angle in any vertical plane. When these screws are tightened, the support 30 is rigidly fastened to the pole.

The upper end of the support 30 is formed with a shelf or table in the middle of which

is a raised rounded boss 32, having a hole therein through which wires may pass. This table of the support 30 is provided with four holes to receive bolts 8^a for securing the casing C thereto. This boss 32 is shaped to fit in the socket formed by the beveled opening 6 in the casing C, and provides in effect a ball and socket connection; and by tightening and loosening the bolts 8^a, the casing C may be tilted with respect to the support 30. Thus, there is provided a coarse and a fine adjustment for setting the signal in any desired angle to throw the beam along the track for a short or long range, up or down grade, and the like. Any signal casing C, either end up, may be attached to the support 30; and by reversing the light projecting unit, including the lens barrel 9, bezel ring 17, lamp receptacle and the hood 15, the same parts may be used to make up a signal in which the doors swing either right or lefthanded.

The lamps 19 may be energized when required by wires (not shown) brought in through the tubular pole, through a hole in the boss 32 of the support 30, and beveled hole 6 into the lower signal casing, and thence to the upper signal casings through the hole 6 in their adjacent walls, bushings 36 of wood or similar insulating material being preferably inserted in these holes as shown in Figs. 1 and 2. Suitable terminal blocks may be provided for facilitating the attachment and connection of wires. The top of the uppermost signal casing 6 is finished with a simple cover plate 38, as shown.

It should be noted that the light projecting unit comprising the lens barrel 9, inner and outer lenses, and lamp receptacle are detachable and interchangeable, so that light projecting units giving different colored indications may be shifted about during installations or after the signals are in service, as may be desired. Changes in the color of the indication of the various units may also be easily made by shifting the lenses, which can readily be taken out after removal of the screws 18 and detachment of the bezel ring 17. While the light projecting units are detachable and interchangeable, each is rigidly attached to the casing and will always come accurately in the proper position in the several signals. Referring to Fig. 2, it will be noted that the lens barrel 9 is formed with an outwardly projecting flange, which is clamped against the outer face of the casing C by the bolts 10. These engaging surfaces and the holes for the bolts are accurately finished during manufacture with the aid of suitable tools and fixtures, so that any given light projecting unit may be attached to any signal casing.

The outer lens 11 can be easily and quickly removed from the outside of the casing by merely taking out the bolts 13 and detaching the hood and outer retaining member 12.

This construction facilitates the replacement of a broken outer lens and also enables the stepped surfaces of the two lenses to be cleaned when necessary. In case of a defective lamp or broken porcelain block 22, rather than replace the block and socket alone, a procedure which might necessitate a re-adjustment of the parts for the best results, a new unit comprising the bezel ring 17, angle bracket 24, block 22 and the socket 21 is substituted for the defective unit, and since these units are identical, it is assured that the new socket shell will be accurately located with respect to the lenses, and upon the insertion of a standardized lamp will position the filament of that lamp at the right point. In short, it will be observed that the signal constructed in accordance with this invention allows any of the various parts likely to wear out, or become damaged in service, to be easily and readily replaced in the field without the need for special adjustment and effectiveness of the signal.

The particular construction of light projector shown and described is susceptible of considerable modification and adaptation in practice, and I desire to have it understood that my invention is not limited to the specific embodiments herein disclosed, except as indicated by the claims.

What I claim is:—

1. In a light signal, in combination, a casing, a lens, means mounting the lens in the casing, a substantially ring shaped lens retaining member bearing directly against the lens and having a downwardly projecting portion, a bracket, means adjustably securing the bracket to said downwardly projecting portion and a lamp socket secured to said bracket.

2. In a light signal, in combination, a casing, a lens, means mounting the lens in the casing, a substantially ring shaped lens retaining member bearing directly against the lens and having two downwardly projecting legs, a bracket adjustably secured to said member by means of bolts passing through slots in said legs, and a lamp socket secured to said bracket.

3. In a light signal, in combination, a casing, a lens, means mounting the lens in the casing, a substantially ring shaped lens retaining member bearing directly against the lens and having two downwardly projecting legs, a bracket adjustably secured to said member by means of bolts passing through vertical slots in said legs, said bracket having a shelf portion extending behind said member at an acute angle thereto, and a lamp socket secured to said shelf portion of said bracket.

4. In a light signal, in combination, a signal casing, a lens, means removably supporting the lens in one wall of the casing, a retaining member for holding the lens in the

supporting means, a lamp receptacle having bayonet slots, and means adjustably supporting said receptacle from said retaining member for adjustment of said receptacle in three planes substantially at right angles to each other, while retaining the relationship of the axis of said lens and the plane defined by the bayonet slots and the axis of said receptacle substantially constant.

5. In a light signal, in combination, a box-like casing having an opening in its front wall, a light projecting unit comprising, a tapered lens barrel, inner and outer stepped lenses seated in circular recesses in the ends of said barrel, a retaining ring for the inner lens, a lamp socket, means supporting the socket on said ring, and a retaining member for the outer lens, said lens barrel having a flange at its outer end and means detachably fastening the flange to the front wall of the casing.

6. A light projecting unit for color light signals comprising, a tapered lens barrel, inner and outer stepped lenses of different diameters supported in said barrel, a retaining member of inverted U-shape for holding the smaller inner lens in position in the lens barrel, a lamp receptacle, and adjustable means supporting said receptacle from said retaining member and permitting movement of the receptacle with respect to said retaining member vertically and horizontally with respect to the axis of said lenses.

7. A light signal unit for railway signalling purposes comprising, a casing having a front wall, the front wall of said casing having an opening therein, a lens barrel in said opening, means securing said barrel to said casing, inner and outer stepped lenses, means securing said lenses in the lens barrel and including an inverted U-shaped retaining member for holding said inner lens in said barrel, said retaining member having downwardly projecting legs, an incandescent lamp socket, and means adjustably securing said socket to said legs.

8. A light signal comprising a signal casing, an opening in one wall of said casing, a lens support secured in said opening, a lens with a simple focal point positioned in said support, a retaining ring secured to said lens support for retaining said lens in said support, and a lamp socket secured to said retaining ring for positioning a light source at said focal point, said lens support and attached parts being removable bodily as a unit from said casing through said opening.

9. In a light signal, the combination of a casing, a lens, means mounting the lens in the casing, a substantially ring shaped retaining member carried by the mounting means and bearing directly against the lens and having two downwardly projecting legs, a bracket, means adjustably securing said bracket to said member including, bolts pass-

ing through vertical slots in said legs, said bracket having a shelf portion extending behind said member, a lamp socket, and means adjustably mounting said socket on

5 said shelf portion.

10. In a light signal, in combination, a casing, a lens, means mounting the lens in the casing, a substantially ring shaped lens retaining member carried by the mounting
10 means and bearing directly against the lens and having two downwardly projecting legs, a bracket, bolt and slot means adjustably securing said bracket to said legs, a lamp socket, and means securing the socket to the
15 bracket.

In testimony whereof I affix my signature.
SALISBURY M. DAY.
